[57] CLAIM

The ornamental design for a combined fish poacher, rack and cover, as shown and described.

DESCRIPTION

FIG. 1 is a top perspective view of a combined fish poacher, rack and cover showing our new design; FIG. 2 is an exploded perspective view thereof, showing the cover (the bottom of which is plain and undecorated), the rack, and the base;

FIG. 3 is a front elevational view of the rack shown separately for ease of illustration, the rear elevational view being a mirror image thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top plan view thereof;

FIG. 9 is a front elevational view thereof;

FIG. 10 is a rear elevational view thereof;

FIG. 11 is a right side elevational view thereof;

FIG. 12 is a left side elevational view thereof; and,

FIG. 13 is a bottom plan view thereof.
